UNITED STATES PATENT OFFICE.

JAMES TAYNTON, OF PORT JERVIS, NEW YORK, ASSIGNOR OF ONE-HALF OF HIS RIGHT TO Z. G. COYKENDALL, OF SAME PLACE.

IMPROVEMENT IN CARRIAGE-CURTAIN FASTENERS.

Specification forming part of Letters Patent No. 123,132, dated January 30, 1872.

SPECIFICATION.

To all whom it may concern:

Be it known that I, JAMES TAYNTON, (assignor to myself and Z. G. Coykendall,) of Port Jervis, in the county of Orange and State of New York, have invented certain new and useful Improvements in Knob-Fasteners for Carriage and other Curtains, Satchel-Clasps, Baldric and Scarf Clasps, and for various other purposes; and the following is a full, clear, and exact description of the same, reference being had to the accompanying drawing making a part of this specification, in which—

Figure 1 represents a curtain of a carriage, showing my improved knob-fastening attached. Fig. 2 shows the frame or clasp for a satchel, with the same kind of knob-fastening. Fig. 3 shows a face view of the knob-fastening, the knob seen in dotted lines. Fig. 4 shows an edge view of Fig. 3. Fig. 5 shows detached sectional views of all the parts—the knob, the plates, and the cap. Fig. 6 shows a sectional edge view of all the parts combined. Fig. 7 shows the knob-fastener with the outer cap or covering removed.

My invention relates to the manner of fastening the curtains to carriages, (or to other places where they are required,) so that they may be easily removed, easily attached, and will be firmly secured so as not to jar loose or become detached of themselves; and it consists of the several parts forming the knob C, the plate h having an elongated opening through it, the rotating slide D, and the cap or cover outside, and the inside plate and flange-plates g and h, for securing the fastener, as hereinafter more fully described. My invention is also applicable to satchel-clasps, baldrics, belts, scarfs, and for various other purposes.

A is the frame, to which the curtain B is attached. a a a are the knob-fastenings, by which the curtain B is held to the frame A at the top, so that the curtain is secure to be rolled up in the usual manner. a' a' are the knob-fastenings to hold the curtain down to the frame at the bottom; they, being made of metal, are constructed and attached to the frame and curtain so as to operate in the following manner. The knob C or button is formed with a

stem of any required length, with a recess, c, turned into it near its outer end. That portion of the stem beyond the groove or recess c is flattened off on both sides, so as to form an oblong button, d. The base of the knob C is provided with a flange, e, and a spike or screw, f, for securing it to the frame A or other places where it may be required. The counterpart or device for fastening the curtain B to the stud or knob C is made of plates and flanges struck out of sheet metal, of such size and form as to fit the stem C, the plates g and h clamping on both sides of the curtain to hold it securely thereto. The plate D is made with the edge struck up at a right angle, i i, the depth of the button d, and has an oblong hole in the central portion just sufficiently large to admit the button d to pass in when in the proper position. The plate D is also provided with a stem, j, projecting from one side of the flange i i, by which it is rotated, so that, when the plate D is turned one-quarter round on the stem C, it, being in the groove c, firmly locks the plate to the stem or stud. A cap or cover, E, is struck up a suitable depth, to go on over the rotating lock-plate D to shield and protect the fastening, and also to make a finish. The caps may be made ornamental or otherwise.

It will readily be seen that my improved method of fastening curtains to carriages or other places, and especially where it is desirable or necessary to remove them occasionally, and for the easy and convenient manner of fastening them down, and their so much greater durability, that they are of great utility, and very superior to those in common use. For fastening the clasps of satchels and traveling-bags, for baldrics, scarfs, and a variety of other purposes, the knob-fastener, as above described, or constructed in a similar manner, may be applied with equal utility. The holes made in curtains to secure them on and fasten them down on carriages soon become worn when buttoned onto the knobs in the usual way, and get loose, unfasten, and flap about; and when new or stiffened by having been wet, or in cold weather, they are very difficult to button, and consequently are often left to swing and flap about, greatly to their own injury and the annoyance of the passengers;

all of which is remedied by my improved knob-fastenings.

What I claim as my invention is—

1. A knob-fastener for carriage-curtains, constructed substantially in the manner herein shown and described.

2. I claim the method of attaching curtains

to carriages or other places with it, as specifically set forth.

JAMES TAYNTON.
